PORTRABLE HOT PLATE

Daniel C. O'Connell, Bedford Village, N. Y., assignor to Sterno, Inc., New York, N. Y., a corporation of New York

Application December 14, 1950, Serial No. 13,430

Term of patent 14 years

(Cl. D81—10)

To all whom it may concern:

Be it known that I, Daniel C. O'Connell, a citizen of the United States, residing at Bedford Village in the county of Westchester, State of New York, have invented a new, original, and ornamental Design for a Portable Hot Plate, of which the following is a specification, reference being had to the accompanying drawing, forming part thereof, in which:

Fig. 1 is a perspective view of the hot plate embodying my new design;

Fig. 2 is a top plan view thereof; and

Fig. 3 is a front elevation thereof; and

Fig. 4 is a side elevation thereof.

The dominant features of the design reside in the portions shown in full lines.

I claim:

The ornamental design for a portable hot plate, as shown and described.

DANIEL C. O'CONNELL.
